Attorney

UNITED STATES PATENT OFFICE.

ARTHUR ADELMAN, OF CHESANING, MICHIGAN.

FUSE.

Application filed October 9, 1924. Serial No. 742,669.

(GRANTED UNDER THE ACT OF MARCH 3, 1883; 22 STAT. L. 625.)

To all whom it may concern:

Be it known that I, ARTHUR ADELMAN, a citizen of the United States, and a resident of Chesaning, county of Saginaw, and State 5 of Michigan, have invented an Improvement in Fuses, of which the following is a specification.

The invention described herein may be used by the Government, or any of its officers 10 or employees in prosecution of work for the Government, or by any other person in the United States, without payment to me of any royalty thereon, in accordance with the act of March 3, 1883.

15 The subject of this invention is a fuse.

The primary object of the invention is to provide a sensitive striker carrying a fixed 20 firing pin, which is normally held in unarmed position, movable to armed position by a centrifugally released member which may carry a firing element, and the striker at the same time extended to a position where it will function through statical air 25 pressure to maintain the firing pin in armed position until impact.

To these and other ends, my invention consists in the construction, arrangement, and combination of elements, described hereinafter and pointed out in the claims forming 30 a part of this specification.

Several embodiments of my invention are illustrated in the accompanying drawings, in which,

Fig. 1 is a longitudinal sectional view 35 of a fuse constructed in accordance with the invention;

Fig. 2 is a sectional view taken on the line 2—2 of Fig. 1;

Fig. 3 is a longitudinal sectional view 40 showing a modified form of locking mechanism; and

Fig. 4 is a horizontal section on the line 4—4 of Fig. 3.

Referring to the drawings by numerals 45 of reference:

A fuse body 10 is formed with a transverse passage 11 into which is inserted a cylindrical bolt 12 formed with a reduced extension 13 which is adapted to pass 50 through an aperture 14 in the fuse body. The extension 13 and the aperture 14 may be squared to prevent rotation of the bolt. The bolt is confined in the passage 11 by

means of a plate 15 suitably closing the opening.

One end of the bolt is provided with an aperture 16, in which is frictionally retained a cup 17 carrying a firing element consisting of a primer 18 and a detonator 19. The primer may be protected by a disc 18'.

The bolt is maintained in unarmed position by means of pins 20 projecting into slots 21 formed in the bolt and each held in place by a spring 22 confined between the pin 20 and a cup 23, rigidly mounted in a recess 24 in the fuse body. When a projectile equipped with my fuse attains a predetermined rotational velocity, the pins are thrown outward by centrifugal force to permit 70 the bolt, acting under the same force, to slide laterally until stopped by the fuse body when the firing element will be disposed axially of the fuse and in line with a booster charge 25.

The upper portion of the bolt is notched as at 26, the inclined surface 27 of the notch extending to a point adjacent the aperture 16.

The nose portion of the fuse body is recessed to carry a retaining ring 28 crimped into place and in which is slidably mounted a hollow striker head 29 having a central stem 30, the lower portion of which carries the shank 31 of a fixed firing pin 32. The firing pin is formed with a collar 33 interposed between the stem and fuse body and the pin normally extends through an aperture 34 in the fuse body to be disposed in the notched portion of the bolt. As the bolt 90 moves to the left the firing pin is cammed forward until clear of the bolt and extrudes the striker until an annular flange 35 formed thereon engages the inturned rim of the retaining ring.

The forward portion of the stem is enlarged and hollowed exteriorly as at 36 and provided with ports 37 to permit the influx of air into the striker head. The walls of the striker head are formed with apertures 38 which are in advance of the fuse body when the striker is in armed position to permit the passage of air therethrough.

The firing pin is held in armed position by the static air pressure which is developed 105 in the hollow striker head when extruded.

The air pressure exerting a constant force in all directions overcomes dynamic pressure on the exterior face of the striker head, since its ogival shape serves to deflect a part of the force of the air current. When the fuse comes in contact with any object having an appreciable resistance to impact, such as an aeroplane fabric, the striker and firing pin will be moved rearwardly to prime the primer and detonate the detonator.

In the modified form shown in Figures 3 and 4, a fuse casing is formed with a hollowed head having an apertured nose for the reception of the striker which carries the fixed firing pin.

A member 39 in the casing carries a primer and is axially bored to receive the free end of the firing pin. The forward face of the member 39 is formed with a circular depression 40, having a wall 41 oblique to the axis of the fuse to constitute a seat for a locking mechanism which supports the firing pin in unarmed position. The locking mechanism comprises a plurality of segments 42 preferably four in number, arranged symmetrically around the firing pin and held together by split rings 43 disposed in a circumferential groove 44. The limited movement of the striker head prevents the firing pin from being extracted from the locking members.

The segments are formed with inclined surfaces 45 to conform to the oblique wall 41 of the seat 40 and to facilitate assembly, the inclined surfaces are provided at either end of the segments.

When linear acceleration of the projectile ceases the locking members being no longer opposed are free to be moved outwardly through centrifugal force. During this movement the locking members are constrained to move axially as well as radially of the fuse by reason of the oblique wall 41 thereby causing the firing pin to move forwardly to armed position, and consequently, extruding the striker head to functioning position.

On impact the firing pin is free to be moved rearwardly to prime the primer as the segments will be held against the wall of the casing through centrifugal force.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. A fuse including a fuse body, said body formed with a transverse passage and an aperture in communication with said passage, a bolt slidably mounted in the passage and adapted to extend through the

aperture in the body, a firing element disposed in one end of the bolt, said bolt formed with a central notch inclined towards the firing element, means for releasably holding the bolt in unarmed position, a firing pin normally disposed in the notched portion of the bolt and adapted to be cammed forward thereby, a striker head mounted in the nose of the fuse body and adapted to move with the firing pin, and a retaining ring for limiting the forward movement of the striker head.

2. A fuse including a fuse body, said body formed with a transverse passage and an aperture in communication with said passage, a bolt slidably mounted in the passage and adapted to extend through the aperture in the body, a firing element carried in one end of the bolt, said bolt formed with a central notch, means for releasably holding the bolt in unarmed position, a firing pin disposed in the notched portion of the bolt and adapted to be cammed forward thereby, and a striker head disposed in the nose of the fuse body and movable with the firing pin.

3. A fuse including a fuse body, a bolt slidable transversely within the fuse body, a firing element carried in one end of the bolt, said bolt formed with a central notch, means for releasably retaining the bolt in unarmed position, a firing pin normally disposed in the notched portion of the bolt and adapted to be cammed thereby to armed position, and means for holding the firing pin in armed position until impact.

4. A fuse including a fuse body, a bolt slidable transversely of the body, a firing element carried in one end of the bolt, means for releasing said bolt to armed position during flight, a firing pin normally disposed in the path of the bolt and movable thereby to armed position, and a striker head movable in functioning position with the firing pin for holding said pin in armed position until impact.

5. A fuse including a fuse body, a bolt slidable transversely of the body, a firing element carried in one end of the bolt, means for releasing said bolt to armed position, and a firing pin normally disposed in the path of the bolt and movable thereby to armed position.

6. A safety device for fuses including a member slidable transversely of the fuse, a firing element in said member, and a firing pin adapted to be moved to armed position by the member.

7. A fuse including an air balanceable striker head, a fixed firing pin in said striker, and means operable during flight for extruding the striker to functioning position to hold the firing pin in armed position, said means including a firing element.

ARTHUR ADELMAN.
